G. B. M. SMITH

VALVE SEAT PULLER

Filed July 16, 1925

Inventor:
George B. M. Smith.
Att. A. D. Pearson
Attorney.

UNITED STATES PATENT OFFICE.

GEORGE B. M. SMITH, OF TORRANCE, CALIFORNIA.

VALVE-SEAT PULLER.

Application filed July 16, 1925. Serial No. 44,095.

My invention relates to valve-seat pullers, and the general object thereof is to provide a simple device for effectively pulling worn valve seats, such as used in water pumps or 5 slush pumps, without injuring the pump in any way.

A more particular object is to provide a valve-seat puller of the character stated operable by pressure, such as the pressure of 10 a screw.

A further object is to provide a hand grip for conveniently and readily opening and closing the jaws of a valve-seat puller.

The invention consists in the features of 15 construction, combination of elements, and arrangement of parts hereinafter described and pointed out in the claims.

Referring to the annexed drawing in which my invention is illustrated and which 20 forms a part of this specification—

Figure 1 is a side elevation of my invention shown in position for pulling a valve seat,

Fig. 2 is a fragmentary edge view of the 25 valve puller, and

Fig. 3 is a horizontal section of the valve puller taken on line 3—3 of Fig. 1.

My valve-seat puller comprises a base member 1, a cross-head 2, a pair of pulling 30 jaws 3, and a screw 4.

The jaws 3 are pivotally mounted near their upper ends in grooves 5 in the ends of the cross-head 2 on pivots 6. The lower ends of the jaws 3 are formed with shoulders 7 35 on their outer edges. Handles 8 are formed on the upper ends of the jaws 3 for swinging the jaws open or closed. The base 1 is provided with a recess 9 in its upper side having a spherical bottom or seat 10 into which recess extends the lower end portion 11 of the screw 4, the lower extremity of which end portion is spherical and rests upon the spherical seat 10. Said lower end portion has an annular groove 12 therein to receive 40 the end of a set-screw 13 seated in the base 1 whereby the lower end of the screw is turnably connected to said base.

The base 1 is formed with a pair of wings 14 on opposite sides thereof, one of 45 which wings extends over one side of one

jaw 3 while the other wing extends over the other side of the other jaw, whereby the base 1 is prevented from turning with the screw 4.

The screw 4 extends through the cross-head 2 between the jaws 3 and is in threaded engagement with said cross-head. A flat-sided head 15 is formed on the upper end of the screw 4 to receive a wrench 16 for turning the screw. 55

To pull a valve seat as indicated at 20, with my puller, the handles 8 are first pressed outwardly and the jaws 3 swung towards each other; the jaws are then introduced through the seat until the base 1 rests 60 upon the top 21 of the pump 22; the handles 8 are then pressed inwardly until the jaws engage the inner surface of the seat with the shoulders 7 of the jaws underneath the lower edge of the seat; the screw 4 is then 65 rotated by means of the wrench 16 which applies an upward pressure upon the jaws, and the engagement of the lower edge of the seat by the jaw shoulders 7 draws the seat 70 upwardly, thus pulling the seat. 75

I claim—

1. A valve-seat puller comprising a cross-head, a screw in threaded engagement with said cross-head, a base to which the lower end of the screw is turnably connected, said 80 base being adapted to rest upon the top of a pump, and a pair of jaws pivoted to said cross-head to be introduced through a valve seat, said jaws including shoulders for engaging the lower edge of said seat. 85

2. A valve-seat puller comprising a cross-head, a screw seated in said cross-head, a base to which the lower end of the screw is turnably connected, said base being adapted to rest upon the top of a pump, a pair of 90 jaws pivoted to said cross-head to be introduced through a valve seat, said jaws including shoulders for engaging the lower edge of said seat, and wings on said base for engaging opposite sides of said jaws respectively to prevent the base from turning. 95

3. A valve-seat puller comprising a base provided with a recess having a lower spherical wall, a screw formed with a cylindrical lower end portion having a spherical ex- 100

tremity adapted to fit in said recess with said spherical extremity resting upon said lower spherical wall, said end portion having an annular groove, a set-screw in said base engaging said groove, a cross-head in which said screw is seated, and a pair of jaws pivoted to said cross-head to be in-

serted through a valve seat and formed with shoulders for engaging the lower edge of said seat.

10

In testimony whereof I hereunto affix my signature.

GEORGE B. M. SMITH.
